DESIGN FOR A DOUGH PRODUCT

Vincent De Palo, Brooklyn, N. Y.

Application September 22, 1933. Serial No. 49,321

Term of patent 7 years

To all whom it may concern:

Be it known that I, VINCENT DE PALO, a citizen of the United States, and residing at Brooklyn, county of Kings, and State of New York, have invented a new, original, and ornamental Design for a Dough Product, of which the following is a specification, reference being had to the accompanying drawing, forming part thereof.

Figure 1 is a top plan view of a dough product, showing my new design,

Figure 2 is a side elevational view thereof, Figure 3 is a bottom plan view of the same, and Figure 4 is an end elevational view thereof.

I claim:

The ornamental design for a dough product, as shown.

VINCENT DE PALO.
